Inventor
William H. Plunkett
By Grafton Wilson Atty.

Patented Nov. 11, 1924.

UNITED STATES PATENT OFFICE.

WILLIAM H. PLUNKETT, OF CHICAGO, ILLINOIS.

DUST MOP.

Application filed January 27, 1922. Serial No. 532,080.

To all whom it may concern:

Be it known that I, WILLIAM H. PLUNKETT, a citizen of the United States, residing at Chicago, in the county of Cook and State 5 of Illinois, have invented certain new and useful Improvements in Dust Mops, of which the following is a specification.

This invention has reference to dust mops adapted for cleaning floors and other surfaces, mops of this general character being sometimes called oil mops.

This invention relates to certain improvements in the general type of mop disclosed in United States Patent No. 1,155,564, 15 granted October 5, 1915.

It is a desideratum of mops of this character that the mop body or swab, as it is customarily termed, which is composed of fibrous strands, be readily detachable from the mop frame in order that it may be boiled and washed when required and also in order that it may be replaced by a new swab when the old one becomes unduly worn.

One of the primary purposes of my present 25 invention is to provide a mop comprising a detachable swab, which swab and the frame are so constructed that the swab may be quickly applied and securely attached thereto so that it will not become accidentally dis- 30 placed but at the same time may be easily and quickly removed when occasion requires.

For the purpose of facilitating an understanding of my invention, I have illustrated 35 in the accompanying drawings one preferred embodiment thereof from an inspection of which, when considered in connection with the following description, my invention and many of its inherent advantages should be 40 readily appreciated.

Referring to the drawings—

Fig. 1 is a plan view of the mop embodying my invention;

Fig. 2 is a side elevation thereof;

Fig. 3 is a perspective view of the mop frame;

Fig. 4 is a sectional view on the line 4—4 of Fig. 2;

Fig. 5 is an enlarged detail view of one 50 of the connections between the handle shank and the frame; and

Fig. 6 is a sectional view of the fastener by which the swab is detachably secured to the frame.

55 Referring now to the drawings more in detail, reference character 7 indicates gen-

erally the frame of the mop which, as shown, is of general U-shape comprising the substantially parallel side members 8 and 9 joined at one end by a transversely extending cross member 11 forming a right angle juncture with the side members, the opposite ends of the side members being bent outwardly in opposite directions to form fingers which can be introduced into crevices or behind furniture legs and the like to enable the cleaning of surfaces which are ordinarily inaccessible to the usual mop.

The handle 12 has its lower end inserted into the circular portion of the shank 13, 70 which is preferably formed of sheet metal and bifurcated to provide the spaced prongs or bifurcations 14 and 15 adapted to be disposed between the side members of the frame. These prongs are connected to their 75 respective adjacent side members by rivets 16, a flat washer 17 being disposed outside the prong and a spring washer 18 being positioned upon the rivet between such washer and its enlarged end 20. This construction 80 provides a pivotal connection between the handle and the frame permitting the handle to be swung into any desired angular position with respect to the mop body, and the spring washers 18 impose such friction between the handle shank and the frame that the mop body will be retained at any desired angle with respect to the handle which may be convenient for cleaning purposes.

The swab comprises an elongated binding 90 portion 19, preferably formed of fabric to which the mop strands 21 are fixedly attached. This binding is constructed to provide pockets closed at the outer ends of the binding and open at points remote from the 95 ends into which the ends of mop frame are inserted, as will be apparent from Fig. 1. The central portion of the binding is provided with a latch adapted to cooperate with an aperture 22 formed in the frame cross 100 member 11. This latch is best shown in Fig. 6 from which it will be apparent that it is in the form of a shank equipped at one end with a stud or rivet 23 adapted to be inserted through one or more layers of the binding 105 19 and through a washer 24 over which the ends of the stud are riveted to securely attach the fastener to the binding. The projecting shank portion 25 of the latch is so proportioned as to be capable of insertion 110 through the aperture 22, and in this shank portion there is pivotally mounted at 26 a

latch member 27 provided with a locking shoulder 28 which member is normally held in the elevated position shown in Fig. 6 by a spring 29.

5 In order to attach the mop swab to the frame the diverging fingers of the frame are introduced into the pockets as previously described, whereupon the central portion of the swab is pulled over the closed end of the 10 frame and the fastener is projected through the aperture 22 until the shoulder 28 snaps upwardly into engagement with the margin of the aperture, thus locking the swab to the frame. When it is desired to remove the 15 swab the latch member 27 may be manually depressed to free the shoulder 28 from the marginal wall of the aperture 22, whereupon the fastener may be withdrawn from this aperture so as to free the swab from the 20 frame.

It will be apparent from the foregoing that I have provided a mop having a detachable swab which can be quickly applied to the frame and when applied is securely 25 locked thereto against accidental displacement. When removal is desired it may be effected by simply manipulating the latch member, whereupon the swab may be detached from the frame. The connection between the handle and the frame is strong 30 and durable and affords sufficient friction

to hold the member in any desired adjusted position.

I claim:

1. A mop, comprising a substantially U- 35 shape frame having an aperture therein and having the ends of its side members bent outwardly away from each other, a mop swab provided with pockets adapted to receive said frame ends, and a latch carried 40 by said swab and adapted to be detachably engaged with said aperture to lock said swab to the frame.

2. A mop, comprising a U-shape frame including a pair of side members united at one 45 end by a cross member joined at right angles to the side members and provided with an aperture, a swab attached to said side members, and a resiliently urged locking device secured to the center of the swab and adapted 50 to enter said aperture for locking the swab to said cross member.

3. A mop, comprising a U-shape frame provided at the closed end thereof with an aperture, a swab adapted to be attached to the free ends of said frame, a shank carried by said swab, and a pivoted latch mounted in said shank to be engaged with the margins of said aperture whereby the swab is 55 locked to the frame.

WILLIAM H. PLUNKETT.
